APPARATUS FOR POLISHING SHEET MATERIAL

Filed Dec. 13, 1926

2 Sheets-Sheet 2

UNITED STATES PATENT OFFICE.

JOSEPH H. WALCOTT, OF SALEM, MASSACHUSETTS, ASSIGNOR TO HELBURN THOMPSON COMPANY, OF SALEM, MASSACHUSETTS, A CORPORATION OF MASSACHUSETTS.

APPARATUS FOR POLISHING SHEET MATERIAL.

Application filed December 13, 1926. Serial No. 154,318.

This invention pertains to the treatment of sheet material and more particularly to apparatus for brushing or polishing such material, and in the exemplification of means here chosen for illustration is applied to the polishing of leather.

It is customary to finish certain fine leathers, particularly those having a pebbled or grained surface, by brushing them with a bristle brush which imparts a gloss not only to the tops of the minute elevations upon the surface of the leather but also to the sides of the depressions or valleys between the elevations. In my Patent No. 1,556,051, dated October 6, 1925, I have disclosed a machine which, as illustrated and described in the patent, is designed primarily for rubbing the surface of leather so as to produce a dull gloss by polishing the tops only of the elevations of its surface. The present invention constitutes an improvement over that disclosed in said patent and while, as here illustrated, it is provided with a brush for polishing the leather, it may be employed for the same purpose as the patented machine merely by substituting a rubbing roll for the brush.

In using a rubbing or polishing roll or brush driven at high speed, I find that the air delivered centrifugally by the brush or roll interferes with the feeding of the leather into contact with the brush, since the air current flowing from the brush tends to raise the advancing edge of the leather from the feed belt and if it does not actually blow the leather back away from the brush, it tends to fold, wrinkle or twist it so that the leather no longer lies flat and in proper shape for the polishing operation.

In my patented machine I provide a resilient support for the feed belt at a point immediately below the polishing or rubbing roll. As disclosed in the patent this support consists of a cylindrical brush engaging the under surface of the belt. Theoretically this supporting brush should rotate by reason of its contact with the moving belt, but as a practical matter I have found that very slight changes in the relative positions of the parts such, for example, as may be caused by warping of the wooden core of the supporting brush or improper adjustment of its shaft may cause it to wear in a non-uniform manner and as this wear

progresses the brush eventually becomes so worn at one side that it no longer finds driving contact with the belt. The brush thus remains practically stationary and such contact as the belt may then have with the brush merely increases the unsymmetrical wear of the brush so that the brush soon fails to provide the proper support for the belt.

In accordance with the present invention I overcome the above difficulties and also secure a further improved operation by providing for holding the leather securely against the surface of the moving belt so that it is not readily swept from the belt by the action of the polishing brush whose peripheral speed is greater than that of the belt.

In the accompanying drawings I have illustrated a desirable embodiment of the invention by way of example and in such drawings,

Fig. 1 is an end elevation of the improved machine viewed from its left hand side;

Fig. 2 is a front elevation of the machine showing the brush housing in vertical section;

Fig. 3 is a plan view of the machine, showing a portion of the brush housing broken away; and

Fig. 4 is a fragmentary vertical section on the line 4—4 of Fig. 3, to larger scale, showing the relation of the supporting and polishing brushes and the guard means.

The machine comprises spaced end frames 1 and 2 held in proper relative position by means of suitable transverse rails or bars 3, 4 etc.

At the front of the machine I provide a shaft 5 carrying a roll 6 and at the rear of the machine I provide a second shaft 7 substantially parallel to the shaft 5 and carrying a roll 8. The shafts 5 and 7 are preferably mounted in adjustable bearings 9 and 10 respectively by means of which the shafts may be brought into accurately parallel relation.

At the central lower part of the machine I provide a transverse shaft 11 which carries an arm 12 at each end. The shaft 11 is free to turn and the arms 12 thus tend to swing downwardly by gravity from the position indicated in Fig. 1. The arms 12 have adjustable bearings 13 supporting a transverse shaft 14 carrying a roll 15. The

shaft 14 is adjusted so as to be parallel to the shafts 5 and 7. An endless conveyor belt 16 of any suitable material, for example heavy canvas or the like, passes about the several rolls 6, 8 and 15, the latter roll constituting tensioning means to keep the conveyor belt taut. That run of the belt which extends from the roll 6 to the roll 8 is preferably substantially horizontal and moves from the front of the machine toward the rear or, as viewed in Fig. 1, from right to left.

At the central upper part of the machine I provide brackets 17 and 18 on the frames 1 and 2, respectively, which support adjustable bearings 19 and 20 for a rotary shaft 21. This shaft carries a drive pulley 22 at one end adapted to receive a driving belt of usual character.

At its opposite end the shaft 21 carries a small sprocket wheel 23. A sprocket chain 24 passes over this sprocket wheel and about an idler sprocket wheel 25 carried by a stud shaft 25^a mounted in bearings 26 (Fig. 3) supported by brackets 27 on the frame member 1. The chain 24 also passes beneath a tensioning sprocket wheel 28 carried by a bracket 29 pivotally supported at 30 upon the frame member 1.

The chain 24 passes around a sprocket wheel 31 mounted upon a stub shaft 32 carried by a bracket 33 secured to the forward part of the frame member 1 and from the sprocket 31 the chain passes rearwardly over a sprocket 34 mounted upon a shaft 35 extending transversely across the machine substantially in the vertical plane of the shaft 21 and below the latter. The shaft 35 is supported in suitable bearings 36 and 37 (Fig. 2) carried by the frame members 1 and 2 respectively.

The shaft 21 carries a brush wheel 38 of any suitable kind, if desired having its bristles arranged in spirally extending tufts, although this is not necessary. As here shown the brush is of ordinary type. The shaft 35 carries a bristle brush 39 which is directly below the belt 16 and normally contacts with the under side of the belt at a point directly beneath the brush 38. The latter brush is substantially tangent to the upper surface of the belt 16.

A small pinion 40 is secured to the sprocket 31 and meshes with a pinion 41 on the shaft 5 of the roller 6. The ratio of diameters of the several sprocket wheels and gears is such that the peripheral speed of the brush 38 is substantially greater than the speed of the belt 16, while the peripheral speed of the brush 39 is preferably considerably less than that of the brush 38. The brush 38 turns in a right hand direction, as viewed in Figs. 1 and 4, and thus its periphery at its point of contact with the belt 16 moves in the same direction as the latter.

I prefer to enclose the upper part of the brush 38 within a housing 42 conveniently formed of sheet metal and having its forward edge secured to a bar 43 (Fig. 4) extending transversely across the machine between the frames 1 and 2. Preferably the bar 43 is provided at its opposite ends with brackets which are secured to the frame members 1 and 2. The rear edge of the housing may likewise be secured to a rod 75 or bar 44 attached at its ends to the frame members.

A bar 46 extends across the machine between the brackets which hold the bar 43 in place, and this bar 46 is preferably adjustably mounted by means of bolt and slot connections, as indicated for example at 45. The bar 46 supports the upper or forward edge of a strip of flexible material indicated at 47. This may be a strip of leather, rubber, canvas, or the like and its free rear edge extends down into the dihedral angle formed by the approaching surfaces of the brush 38 and the belt 16. Preferably the guard strip 47 inclines downwardly and rearwardly 90 so as to leave a flaring space 48 below it for the entrance of the advancing edge of the leather 49.

In operating the machine the operator places a piece of leather upon the upper run of the belt 16 and as the belt travels rearwardly it feeds this leather into the space 48 between the guard member 47 and the belt. The guard member 47 prevents the air thrown out centrifugally by the rapidly rotating brush 38 from getting under the advancing edge of the leather so that the latter moves with the belt until it is brought into contact with the under surface of the guard member 47. As the air thrown out by the brush engages the upper surface of this flexible member 47 it presses the free edge of the latter downwardly toward the upper surface of the belt 16 and thus as the edge of the leather moves into the angle between the member 47 and the belt the leather is very firmly held down against the belt so that it is constrained to move at the same speed as that of the belt and no faster.

As the forward portion of the leather continues to move, it passes from below the guard 47 and into contact with the bristles of the brush 38 and is subjected to the polishing and brushing action of the latter. Since the rear portions of the leather still engage the member 47, the brush 38 can not sweep the leather along faster than the belt 16 and thus the polishing action is continued over the entire surface of the leather.

During the movement of the leather beneath the brush 38, the belt 16 is supported by means of the brush 39 in the same way as described in my previous patent above referred to, but as the brush 39 is positively

driven it can not readily wear unevenly even though it may be warped to some extent or its shaft thrown out of adjustment, so that even after a long period of use it furnishes 5 a proper and uniform support for the belt at the working point.

In accordance with the material being operated upon and particularly to compensate for variations in thickness, I may adjust 10 the position of the bar 46 and the guard 47 carried thereby, and likewise by changing the sprocket wheels and gears upon the shafts, I may if desired vary the ratio of the speeds of the brushes and belts in accordance 15 with circumstances.

While I have described the part 47 as flexible, it may be found desirable under some circumstances to use a rigid and inflexible element at this point, such a rigid 20 element protecting the advancing leather from the air currents delivered by the brush, although it would not press the leather against the belt 16 in the way that a flexible strip will do.

While I have illustrated one specific embodiment of the invention herein, I wish it to be understood that various changes in proportions of parts and materials employed 25 may be made without departing from the spirit of the invention, and that although leather has been referred to specifically as the material to be treated, any other material may be operated upon by the machine in the same manner.

I claim:

1. A machine for polishing sheet material comprising a rotating brush, means substantially tangent to the periphery of the brush for guiding the sheet material on its way 40 to the brush, and means for shielding the advancing edge of the sheet material from the air delivered centrifugally from the brush.

2. A machine for use in finishing leather comprising a rotary brush roll, an endless 45 conveyor belt having a run substantially tangent to the periphery of the roll for feeding leather to the roll, means for driving the brush roll and belt, and a guard member extending into the angle between the approaching roll and belt, said guard member being oblique to the belt and shielding the leather resting upon the belt from the air delivered by the brush as the leather approaches the brush.

3. A machine for use in finishing leather comprising a brush roll, means for driving the roll at high speed, an endless conveyor belt having a substantially horizontal run substantially tangent to the periphery of the 50 roll, means for driving the belt at a speed relatively less than that of the brush, a housing enclosing the upper part of the brush, a guard strip extending substantially from one end of the brush roll to the other, said strip 55 having a free edge disposed within the angle

of approach of the belt and brush roll, and a bar for supporting the opposite edge of the strip.

4. A machine for polishing sheet material comprising a rotating brush, an element having a surface substantially tangent to the brush for supporting the material, means for rotating the brush, the rotation of the brush tending to move the material bodily in the direction of rotation of the brush, and flexible guard means extending substantially from one end of the brush roll to the other, said guard means having a part disposed closely adjacent to the line of contact of the brush and the supporting means for frictionally retarding the material. 70

5. A machine for polishing sheet material comprising a rotary brush, a support having a surface substantially tangent to the brush, means for rotating the brush, the rotation of the brush tending to move the material bodily in the direction of rotation of the brush, and pneumatically actuated friction break means for retarding the material and for holding it against the supporting means. 85

6. A machine for polishing sheet material comprising a rotary brush, a conveyor belt for supporting the material, and means actuated by the air delivered centrifugally by the brush for pressing the material against 90 the conveyor belt.

7. A machine for use in finishing leather comprising a rotating roll, an endless conveyor having a run substantially tangent to the periphery of the roll, means for driving the belt at a speed less than the surface speed of the roll and in the same direction, and a flexible presser element disposed in the angle between the approaching belt and roll, said presser element responding to the air 100 delivered centrifugally by the rotating roll to press the leather against the belt.

8. A machine for use in finishing leather comprising a rotating roll, an endless conveyor having a run substantially tangent to the periphery of the roll, said conveyor being devoid of penetrating points or prongs, means for driving the conveyor at a speed less than the surface speed of the roll and in the same direction, and stationary means 110 independent of the conveyor constraining the leather to move at substantially the same speed as the conveyor.

9. A machine for use in finishing leather comprising a rotary brush roll, an endless conveyor belt having a run substantially tangent to the periphery of the roll, means for driving the brush roll and belt, and a strip of flexible material having one edge disposed within the dihedral angle formed by the approaching brush and belt, said edge normally resting upon the belt, and means supporting the opposite edge of said strip at a point spaced from the belt. 115

10. A machine for use in finishing leather 120

comprising a rotary brush roll, an endless conveyor belt having a run substantially tangent to the periphery of the roll, means for driving the brush roll and belt, a strip of flexible fabric having a free edge normally resting upon the belt within the angle of approach of the belt and brush roll, and an adjustable bar supporting the opposite edge of said strip, the latter edge being spaced above the belt to provide a passage below it for leather resting upon the belt.

11. A machine for polishing sheet material comprising a polishing appliance, an endless flexible conveyor for feeding the material to the polishing appliance, a rotary resilient support for the sheet material at a point opposite to the polishing appliance, and means for positively rotating the resilient support and for driving the conveyor.

12. A machine for polishing sheet material comprising a rotary polishing brush, an end-

less belt conveyor for feeding the material to be treated to the brush, a rotary roll having a resilient surface disposed at the opposite side of the belt from the brush and tending to press the belt against the brush, means for rotating the brush, and positive means for rotating the resilient roll and the belt conveyor.

13. A machine for polishing sheet material comprising a power-driven rotary polishing brush, a horizontally moving belt for feeding the sheet material to the brush, means for driving the belt at a speed less than the surface speed of the brush, a supporting brush roll parallel to the polishing brush and disposed below the belt for supporting the sheet material immediately below the polishing brush, and means for positively rotating the supporting brush roll.

Signed by me at Salem, Massachusetts, this ninth day of December, 1926.

JOSEPH H. WALCOTT.
